UNITED STATES PATENT OFFICE.

THOMAS J. HART, OF BUFFALO, NEW YORK, ASSIGNOR TO SHERWOOD MANUFACTURING COMPANY, OF BUFFALO, NEW YORK.

FLUE-CLEANER.

SPECIFICATION forming part of Letters Patent No. 705,753, dated July 29, 1902.

Application filed October 28, 1900. Serial No. 34,428. (No model.)

To all whom it may concern:

Be it known that I, THOMAS J. HART, a citizen of the United States, residing at Buffalo, in the county of Erie and State of New York, 5 have invented new and useful Improvements in Tube-Cleaners, of which the following is a specification.

This invention relates to that class of boiler-tube cleaners which are provided with rotary 10 cutters for removing the scale from the inner side of the water-tubes of boilers, said cutters being rotated by a turbine which is operated by steam or some other actuating fluid.

The object of my invention is to provide 15 the cleaner with an improved centering device which is thrown out against the tube by the pressure of the actuating fluid which operates the cutter and which centering device is simple in construction and reliable and effective in operation.

In the accompanying drawings, Figure 1 is a longitudinal sectional elevation of my improved tube-cleaner, showing the same arranged in a curved boiler-tube. Figs. 2, 3, 25 and 4 are transverse sections in line 2 2, 3 3, and 4 4, Fig. 1, respectively. Fig. 5 is a detached view of the spherical knuckle of the universal joint which connects the pressure-tube with the case of the cleaner.

30 Like letters of reference refer to like parts in the several figures.

A represents the portion of a boiler-tube in which the cleaner is arranged and which is shown partly straight and partly curved.

35 B represents the hollow shell, body, or casing of the cleaner, which is preferably enlarged at its front and rear ends and contracted at its middle.

C represents the rotary head, which is journaled at its rear end on a diaphragm D in the front end of the casing.

40 E represents the cutter-arms, which are pivoted on the head and which are provided with the usual serrated cutter-disks e. Upon 45 rotating the head when the cleaner is in a tube the cutter-arms are thrown outwardly by centrifugal force and the cutter-disks engage with the inner side of the boiler-tube and remove the scale therefrom. The cutter-head is rotated by steam or other fluid under 50 pressure, which is supplied to the casing and

issues through openings d in the diaphragm D thereof against a turbine F on the rear part of the rotary head. All of these parts may be of any suitable or well-known construction. 55

G represents a number of centering-arms, which are arranged lengthwise on the outer side of the contracted middle part of the case. Three of these centering-arms are arranged 60 equidistant circumferentially around the case, so as to produce a three-point support of the cleaner in the tube when the cleaner is in operation. Each of these arms is pivoted at its rear end by a transverse pin g to lugs 65 g' on the case and provided at its front end with a roller g'', by which it bears against the inner side of the boiler-tube.

H represents a number of radially-movable plungers or pistons whereby the centering-arms are moved outwardly and which are actuated by the pressure of the steam or other fluid in the case. These plungers are arranged in circular openings or seats h in the case and engage at their outer ends with 70 the inner side of the centering-arms, while their inner ends are exposed to the pressure of the actuating fluid in the case. The arms carrying the cutters are capable of moving outwardly to such a position that their free 75 ends project beyond the largest part of the case. When the centering-arms engage with the inner side of a tube, the case of the cleaner is held out of contact with the tube, whereby the friction and wear are reduced. 80 The outward movement of the centering arms and the plungers is limited by stops i, formed on the centering-arms in rear of the pivots thereof and adapted to engage with the adjacent part of the case. The inward movement of the centering arms and plungers is limited by heads or stops h', formed on the outer ends of the plungers and adapted to 85 engage with the outer side of the case.

Upon admitting steam to the casing of the 90 cleaner after the latter has been introduced into a boiler-tube the pressure of the steam against the inner ends of the plungers forces the same outwardly, and the plungers in turn move the centering-arms outwardly until the 95 same bear against the inner side of the boiler-tube. The pressure against the several cen- 100

tering-arms is uniform, which causes the arms to be moved outwardly simultaneously and to the same distance. The cleaner-case is held centrally in the tube by these devices, and the 5 cutters are thereby caused to operate uniformly on the scale in the tube.

In inserting the cleaner into a tube and in withdrawing the cleaner after the tube has been cleaned the actuating fluid is shut off 10 from the case and the centering-arms are collapsed and free to move in and out. This allows the cleaner to be easily moved into and out of the tube.

When the cleaner is required to pass 15 through tubes which have comparatively short bent or curved portions, the case is connected by a spherical joint with the pipe or hollow handle which supplies the pressure-medium to the cleaner. This permits the 20 cleaner to arrange itself at a considerable angle to the pressure-tube and enables the cleaner to pass around short curves. This joint is constructed as follows:

K represents the flexible pressure-tube or 25 hollow handle, whereby the pressure medium—such as steam, air, or water—is conducted into the hollow case of the cleaner.

L represents a hollow spherical knuckle which is open at its front and rear ends and 30 provided on its rear side with a tubular nipple l, which enters the front end of the pressure-pipe. This nipple is provided with an external flange or collar l', which abuts with its rear side against the front end of the 35 pressure-tube.

M represents clamping-bars whereby the pressure-pipe is coupled with the nipple l. Two of these bars are preferably arranged 40 lengthwise on opposite sides of the pressure-pipe and the collar l', and each bar is provided at its front end with an inwardly-projecting hook or lip m, which engages with the front side of the collar l'. The clamping-bars are clamped against opposite sides of the 45 pressure-pipe and the latter against opposite sides of the nipple by a split clamping-band N, which encircles the clamping-bars and the pressure-pipe. The ends of the clamping-band are provided with perforated ears, which 50 are connected by a clamping-bolt n. The clamping-band is preferably provided with seats n', which receive the clamping-bars, and also with inwardly-projecting teats or 55 projections n², which engage with recesses or openings n³ in the clamping-bars, as shown in Figs. 1 and 4, thereby preventing the band from slipping lengthwise from the clamping-bars. In order to permit the pressure-tube to obtain a firm grip upon the nipple l, the

outer side of the latter is corrugated, as 60 shown at o, Fig. 1.

P P' represent, respectively, the fixed and removable sections of a spherical socket, which is arranged at the rear end of the case of the cleaner and which receives the spherical 65 knuckle of the pressure-pipe. The fixed section P of the socket is formed directly on the rear end of the hollow case of the cleaner, and the removable section P' is secured by bolts p to the fixed section. This ball-and- 70 socket joint between the pressure-pipe and the cleaner permits the latter considerable freedom of movement with reference to the pressure-pipe.

I claim as my invention—

1. The combination with the hollow case of 75 a tube-cleaner adapted to receive a pressure fluid, and the cutter medium mounted on the case, of centering-arms arranged on the outer side of said case, and plungers which are 80 guided in said case and engage with said arms and are pressed outwardly by the pressure fluid, substantially as set forth.

2. The combination with the hollow case of 85 a tube-cleaner adapted to receive a pressure fluid, and the cutter medium mounted on the case, of centering-arms pivoted on the outer side of the case, plungers which engage with 90 said arms and are pressed outward by the pressure fluid, and stops whereby the inward and outward movement of the arms and plungers is limited, substantially as set forth.

3. The combination with the hollow case of 95 a tube-cleaner adapted to receive a pressure medium, and a rotary cutter mounted on the case, of centering-arms arranged lengthwise on the outer side of the case and pivoted at one end to the same while the opposite end is provided with a roller which is adapted to bear against the inner side of the tube to be 100 cleaned, centering-plungers guided in the hollow case and projecting with their inner ends into the interior of the case while their outer ends bear against the centering-arms, 105 stops arranged on the centering-arms and adapted to engage the case for limiting the outward movement of the arms and plungers, and stops arranged on the plungers and adapted to engage the case for limiting the inward movement of the arms and plungers, 110 substantially as set forth.

Witness my hand this 24th day of October, 1900.

THOMAS J. HART.
